CLAIM

The ornamental design for a kitchen storage, as shown and described.

DESCRIPTION

FIG. 1 is a front, top perspective view of a kitchen storage, showing my new design;

FIG. 2 is a rear, bottom perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a partial enlarged view of FIG. 2;

FIG. 9 is a partial enlarged view of FIG. 2;

FIG. 10 is a partial enlarged view of FIG. 3;

FIG. 11 is a partial enlarged view of FIG. 4;

FIG. 12 is a partial enlarged view of FIG. 7;

FIG. 13 is a front, top perspective view of the kitchen storage in a detached state;

FIG. 14 is a partial enlarged view of FIG. 13;

FIG. 15 is a partial enlarged view of FIG. 13;

FIG. 16 is a partial enlarged view of FIG. 13; and,

FIG. 17 is a partial enlarged view of FIG. 13.

The dashed broken lines in the figures are for the purposes of illustrating portions of the kitchen storage, which form no part of the claimed design.

The dash-dot-dash broken lines are for notating enlarged views, and form no part of the claim design.

1 Claim, 16 Drawing Sheets
